US00D535920S

(12) **United States Design Patent** (10) **Patent No.:** **US D535,920 S**
Tomcany et al. (45) **Date of Patent:** **** Jan. 30, 2007**

(54) **PAD FOR HEAD AND NECK RESTRAINT**

(76) Inventors: **Brian Tomcany**, 19431 Blue Spruce Dr., Strongsville, OH (US) 44149; **Ronald Rich**, 16233 Roselawn Dr., Burton, OH (US) 44021

(**) Term: **14 Years**

(21) Appl. No.: **29/209,955**

(22) Filed: **Jul. 23, 2004**

(51) **LOC (8) Cl.** **12-12**

(52) **U.S. Cl.** **D12/133; D24/191**

(58) **Field of Classification Search** D12/133; D24/191; 297/284.1, 284.3, 284.4, 284.7; 602/5, 6, 17, 18; 128/869, 870

See application file for complete search history.

(74) Attorney, Agent, or Firm—Wood, Herron & Evans, LLP

(57) **CLAIM**

The ornamental design for a pad for head and neck restraint, as shown and described.

DESCRIPTION

FIG. 1 is a front perspective view of the pad of the design invention shown being positioned in a head and neck restraint paddle, which is shown in dash-dot lines or phantom form;

FIG. 2 is a front view of the pad of FIG. 1; the rear view is a mirror image;

FIG. 3 is a left side elevational view of the pad of FIG. 1; FIG. 4 is right side elevational view of the pad of FIG. 1; FIG. 5 is a top view of the pad of FIG. 1; and, FIG. 6 is a bottom view of the pad of FIG. 1.

The elements shown in dash-dot lines or phantom form no part of the claimed invention in this application, and are instead included to show environmental aspects of the design of the claimed invention.
